UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,278,697.

Specification of Letters Patent. Patented Sept. 10, 1918.

Application filed November 2, 1917. Serial No. 199,865.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and more particularly to means for establishing a talking connection between a connecting operator and a subscriber.

It is the object of this invention to provide improved means to establish connection from an operator's telephone head-set to a desired link circuit, such means being arranged so as to establish connections quickly and with a small amount of apparatus.

In telephone systems of the semi-automatic type, it has been frequent practice to provide each operator with a plurality of link circuits and to associate with each of said link circuits an auxiliary switch to be used in establishing connection from said link circuits to said head-set.

More specifically, it is the object of this invention to provide an arrangement in which a relatively small number of auxiliary switches will be needed to control the connections between the operator's head-set and the cords at her position.

The cord circuits of a position are divided into groups and associated with each group is an auxiliary automatic switch. In addition there is another automatic switch which we will call a central auxiliary switch. All these switches are arranged to be operated in a hunting movement, the operation being such that when connection from a particular cord to the head-set is desired, all the switches will rotate in a hunting movement, the central switch establishing connection from the head-set to the switch associated with the desired group of link circuits, and the selected auxiliary group switch will then determine to which circuit in the group the head-set connection will be further extended.

The saving in the number of switches required, accomplished by this grouping arrangement, will be more obvious from the following concrete example. If we assume that there are twenty-five cord circuits at an operator's position, and that these are divided into five groups of five each, there

will be required only one auxiliary switch for each group, in addition to the control auxiliary switch, or a total of six switches as against the twenty-five switches which would ordinarily be required.

In previous grouping arrangements of this kind, listening-in was accomplished automatically when the operator answered a call by plugging into the jack of the calling line, but if she desired to relisten in, it was necessary for her to press a listening key and hold it depressed for a sufficient length of time to allow the switches to establish the desired connection.

A feature of the present invention is an arrangement by which the momentary depression of a listening key will cause locking relays to operate and maintain the registration necessary to cause the proper switches to find the desired cord.

A further feature of the invention is the coördinate arrangement of said locking relays so that by energizing a plurality of relays each time a key is depressed, the number of locking relays required will be considerably less than the number of keys.

Further features of the invention reside in the provision of means for disconnecting the head-set from the contacts of the hunting switches while the switches are in motion, in the provision of means for releasing the locking relays at desired times and in other improvements which will appear from the following description.

It is thought that the invention will be best understood from the following detailed description, reference being had to the accompanying drawings.

In the drawings, Figure 1 shows a connecting operator's cord circuit, together with the diagrammatic indication of an automatic switch for extending a desired connection, together with an associated sequence switch for controlling said selector switch. Within the dotted rectangle in the lower portion of Fig. 1 is shown a portion of a sending equipment of a well known type and controlled by a sequence switch, not shown. Fig. 2 shows the listening keys and the locking relays which control the auxiliary switches. Fig. 3 shows the auxiliary switches and the operator's head-set.

The switch diagrammatically indicated in Fig. 1 is similar in structure to that shown in Patent No. 1,123,696, issued January 5, 110

1915 to E. B. Craft and J. N. Reynolds. The sequence switch associated with the selector switch shown in Fig. 1 is of the well-known type disclosed in Patent No. 1,127,808, issued 5 Feb. 9, 1915 to J. N. Reynolds and C. F. Baldwin. The operation of the selector switch and of the controlling sending device indicated in the dotted rectangle in Fig. 1 is similar to that described in Patent No. 10 1,168,319, which issued to applicant on January 18, 1916. The auxiliary switches shown in Fig. 3 are of the well-known sequence switch type as disclosed in the above mentioned Patent No. 1,127,808.

15 It will be assumed that the operator, one of whose cord circuits is shown in Fig. 1, has at her position twenty-four cords, and that these cords are divided into four groups of five cords each and one group of four 20 cords. There will be a listening key associated with each cord and with five group switches and one central switch, twenty-five combinations may be established. The twenty-fifth combination will control the 25 listening-out condition and will be controlled by a listening-out key.

The operation is as follows: The subscriber at substation 1 desiring a connection, removes his receiver from the hook, 30 whereupon line relay 2 will be energized to cause the display of line signal 3 in a well-known manner. The operator, one of whose cord circuits is indicated at O, upon observing the lighting of lamp 3, inserts plug 4 35 into jack 5 of the calling line. A circuit is then completed from grounded battery, winding of relay 6, sleeve contacts of plug 4 and jack 5, winding of cut-off relay 7 to ground. Cut-off relay 7 is energized to re- 40 move control of the line relay from the calling subscriber in the well-known manner. Relay 6 is also energized and completes a circuit from grounded battery, power magnet of sequence switch 8, upper right-hand 45 contact of sequence switch spring 9, armature and front contact of relay 6 to ground, for moving sequence switch 8 out of position 1 and into position 2.

When sequence switch 8 passes through 50 positions $1\frac{1}{2}$ to $1\frac{3}{4}$, a circuit is completed from grounded battery, winding of cord relay 10, conductors 11 and 12, contact of sequence switch spring 13, conductors 14 and 15, left-hand winding of group relay 16, 55 winding of relay 17 to ground. Relays 10, 16 and 17 are energized in this circuit. Relay 16 upon energization completes a locking circuit for itself extending from grounded battery, right-hand armature and front con- 60 tact of relay 16, armature and back contact of relay 18 to ground. Relay 10 upon energization completes a locking circuit for itself, extending from grounded battery, winding of relay 10, left-hand armature and 65 front contact of relay 10, winding of relay

19 to ground at the armature and back contact of relay 18. When sequence switch 8 leaves position $1\frac{3}{4}$, the original energizing circuit of relays 10, 16 and 17 is broken and relay 17 deenergizes, but relays 10 and 16 70 are maintained energized by means of the above described locking circuits.

With relay 19 energized and relay 17 deenergized, parallel circuits are completed for the power magnets of sequence switches 20, 75 21, 22, 23, 24 and 25 respectively. These circuits extend from grounded battery, through the power magnets of said switches respectively, through the right-hand armatures and back contacts of cut-off relays 26, 80 27, 28, 29, 30 and 31, respectively, to conductor 32, armature and front contact of relay 19 and armature and back contact of relay 17 to ground. If it is assumed that the cord circuit shown in Fig. 1 is the first 85 cord in the first group, then when group switch 21 arrives in position 1, a circuit will be completed from grounded battery, winding of relay 27, upper right-hand contact of sequence switch spring 33, conductor 34 90 to ground at the right-hand armature and front contact of relay 10. Similarly sequence switch 22 will be stopped in position 1 by the actuation of relay 28, sequence switch 23 will be stopped in position 1 by the actua- 95 tion of relay 29, sequence switch 24 in position 1 by the actuation of relay 30 and sequence switch 25 in position 1 by the actuation of relay 31. Central switch 20 will be stopped in position 1 to extend the head- 100 set connections to the first group switch, which is switch 21, by means of the actuation of relay 26 over a circuit extending from grounded battery, winding of relay 26, upper right-hand contact of sequence 105 switch spring 35, conductor 36, left-hand armature and front contact of relay 16 to ground. As soon as all the auxiliary switches have been positioned, a circuit will be completed from grounded battery, winding of 110 relay 18, conductor 37, left-hand armature and front contact of relay 27, upper right-hand contact of sequence switch spring 38, left-hand armature and front contact of relay 26 to ground. At the same time, a 115 parallel circuit is completed from grounded battery, winding of relay 39, conductor 40, left-hand armature and front contact of relay 27, upper right-hand contact of sequence switch spring 38, left-hand armature and front contact of relay 26 to ground. The energization of relay 39 extends the head-set connections to switch springs 41 and 42 and since the central auxiliary switch 20 is 120 in its first position, connection will then be extended to the contacts of group auxiliary switch 21. This switch being also in position 1, the head-set connections will be further extended by way of contacts 43 and 44 and conductors 45, 46 to the desired cord cir- 125 130

cuit. Relay 18 upon energization opens the locking circuits of relays 16, 10 and 19 and these relays deenergize. Deenergization of relays 10 and 16 causes in turn the deenergization of relays 26, 27, 28, 29, 30 and 31. Relay 39 is maintained energized by means of a locking circuit extending from grounded battery, winding of relay 39, outer left-hand armature and front contact of relay 39, conductor 47, armature and back contact of relay 17 to ground. Relay 18 is maintained energized in a branch of this locking circuit extending from grounded battery, winding of relay 18, conductors 37 and 40, outer left-hand armature and front contact of relay 39 and thence to ground over the path described.

The connection between the calling subscriber and the operator is now complete and may be traced as follows: from the operator's receiver 48, winding of induction coil 49, inner left-hand armature and front contact of relay 39, upper left-hand contact of switch spring 41, the upper right-hand contact of switch spring 44, conductor 46, ring contacts of plug 4 and jack 5 through the loop of the calling subscriber's line, including the substation apparatus, tip contacts of jack 5 and plug 4, conductor 45, upper right-hand contact of switch spring 43, upper left-hand contact of sequence switch spring 42, right-hand armature and front contact of relay 39, condenser 50, and thence to receiver 48. Talking battery is supplied to the calling subscriber from the battery shown connected to the windings of repeating coil 51. Talking battery for the operator is included in series with the primary winding of induction coil 49 and the transmitter of the operator's telephone set.

The operator may now converse with the calling subscriber and ascertain the number of the wanted line. She will then proceed, as described in the previously mentioned Patent No. 1,168,319, to set up a number on a key set (not shown) to control the switch indicated in Fig. 1 and other succeeding switches.

Assuming that sequence switch 8 is advanced to position 11 after the operation of the selector switch whose brushes are generally indicated at 52, the circuit for controlling the succeeding switches will be extended by means of the lower contacts of sequence switch springs 53 and 54 to the sender indicated generally at 55.

When the sequence switch associated with the sending device reaches position 16, at which time the succeeding switches of the train will have been positioned, a circuit is completed from grounded battery, power magnet of sequence switch 8, lower left-hand contact of sequence switch spring 9, contact of sequence switch spring 56 to ground, for moving sequence switch 8 out of position 11

and into position 16, in which position talking may take place. Upon completion of the conversation the replacing of their receivers by the calling and called subscribers will operate supervisory signals of the well-known type, which signals are controlled by supervisory relays 57 and 58, respectively. The operation of these signals will inform the connecting operator that connection is no longer desired and she will thereupon take down the connection by removing plug 4 from jack 5. The removal of plug 4 from jack 5 causes the deenergization of relay 6, whereupon a circuit is completed from grounded battery, power magnet of sequence switch 8, upper left-hand contact of sequence switch spring 9, armature and back contact of relay 6 to ground, for moving this sequence switch out of position 16 and into position 18.

In position 18, the selector switch 52 and the other switches of the train are restored in the well-known manner. When the selector switch indicated at 52 is returned to its normal position, suitable circuits will be set up for advancing sequence switch 8 into position 1, in readiness for reoperation of the selector switch.

It will now be assumed that the connecting operator, after setting up the connection just described, answers a call with cord 19. When the sequence switch associated with cord 19 passes through positions $1\frac{1}{2}$ to $1\frac{3}{4}$, a circuit will be completed from grounded battery, winding of relay 57, conductor 58, through the contacts of a sequence switch spring corresponding to spring 13 in Fig. 1, conductor 59, left-hand winding of relay 60, winding of relay 17 to ground. Relays 57, 60 and 17 are energized and relays 57 and 60 lock up over circuits similar to those described for relays 10 and 16. At this time the energization of relay 17 will open the locking circuits of relays 18 and 39 and these relays will be deenergized. The energized condition of relays 57 and 60, with relay 19 energized and relay 17 deenergized, will again complete circuits for starting the auxiliary switches. This time the central switch 20 will be stopped in position 4 to select the fourth group, and group auxiliary switches 21, 22, 23, 24 and 25 will be stopped in position 4 to select the fourth cord in the fourth group. Thus it will be seen that in answering another call the operator has been automatically listened out of the cord shown in Fig. 1 and listened in on cord 19.

If now she desires to relisten in on cord No. 1 she will depress listening key No. 1, whereupon circuits for relays 10, 16 and 17 will be completed as previously described, excepting that instead of extending through the contacts of sequence switch spring 13, connection will be directly extended from conductor 11 to conductor 15 through the

closed contacts of listening key No. 1. Since the actuated relays are locked up instantly, it is obvious that only a momentary depression of the listening key is necessary.

- 5 It is to be observed that relay 39 is de-energized during the hunting movement of the switches and therefore the head-set connections are not extended to the wipers of the hunting switches, thus preventing clicks 10 as the switches pass over contacts leading to busy cords.

It will also be noted that by arranging the locking relays on a coördinate basis, that is, pulling up two relays each time that a key 15 is depressed, the number of relays required is relatively few in comparison to the number of keys.

It is obvious that listening-out may be accomplished at any desired time by causing 20 the switches to move into positions such that the head-set connection will simply be extended to unwired contacts on a cord selecting switch. In the arrangement shown it has been assumed that key No. 25 is the 25 listening-out key and therefore the contacts closed in position 5 of the cord selecting switch 25, will not be wired.

It is to be understood that the grouping arrangement shown is merely assumed for 30 the purpose of giving clarity to the description and that any desired number of groups and any number of cords in a group are arrangements within the spirit of the present invention.

- 35 What is claimed is:

1. In a telephone exchange system, a plurality of link circuits arranged in groups, an operator's telephone set, a listening key associated with each of said link circuits, 40 means to extend connection from said telephone set to a desired group, means to further extend said connection to a desired link circuit in a selected group, and means operative upon a momentary depression of one of 45 said listening keys to establish connection from said telephone set to a desired link circuit.

2. In a telephone exchange system, a plurality of link circuits arranged in groups, 50 an operator's telephone set, means to extend connection from said set to a desired group, means to further extend said connection to a desired cord in a selected group, means to automatically establish a listening-in connection when said operator answers a call, 55 a listening key associated with each link circuit cord, means to automatically listen in on a second cord when taken for use, and means operative upon a momentary depression of one of said listening keys to establish 60 connection from said head-set to the link circuit with which said depressed key is associated.

3. In a telephone exchange system, a plurality of link circuits arranged in groups, 65

an operator's telephone set, a listening key associated with each of said link circuits, means to extend connection from said telephone set to a desired group, means to further extend connection to a desired link circuit 70 in a selected group, means to automatically establish a listening-in connection to a link circuit when taken for use, means to automatically disconnect said head-set from said first link circuit when a second link circuit 75 is taken for use, means to automatically establish connection from said head-set to said second link circuit, and means operative upon a momentary depression of one of said listening keys to establish connection from 80 said telephone set to a desired link circuit.

4. In a telephone exchange system, a plurality of link circuits arranged in groups, an automatic switch associated with each of said groups, an additional automatic switch, 85 an operator's telephone set, a listening key associated with each of said link circuits, means to operate said additional switch to extend connection from said telephone set to a desired group switch, means to operate 90 a selected group switch to further extend said connection to a desired link circuit, and means operative upon momentary depression of one of said listening keys to establish connection from said telephone set to a 95 desired link circuit.

5. In a telephone exchange system, a plurality of link circuits arranged in groups, an automatic switch associated with each of said groups, an additional automatic 100 switch, an operator's telephone set, a key associated with each of said link circuits, and means including said switches to extend connections from said telephone set to a desired link circuit under the control of the 105 key associated with said link circuit upon a momentary depression of said key.

6. In a telephone exchange system, a plurality of link circuits arranged in groups, an operator's telephone set, a key associated 110 with each of said link circuits, a plurality of relays, means to actuate certain ones of said relays upon a momentary depression of one of said keys, and means to establish connection from said head-set to a desired link 115 circuit in accordance with which ones of said relays have been actuated.

7. In a telephone exchange system, a plurality of link circuits arranged in groups, an automatic switch associated with each of said groups, an additional automatic switch, 120 an operator's telephone set, a key associated with each of said link circuits, a plurality of relays, means to actuate certain ones of said relays upon a momentary depression of one of said keys, means to operate said additional switch to extend connection from said telephone set to a desired group switch, 125 means to operate a selected group switch to further extend said connection to a desired 130

link circuit, and means to control the extent of motion of said switches in accordance with which ones of said relays have been actuated.

- 5 8. In a telephone exchange system, a plurality of link circuits, a plurality of automatic switches, an operator's telephone set, a plurality of locking relays less in number than said link circuits, means to actuate said
- 10 automatic switches under the control of said locking relays to extend connection from said telephone set to a desired link circuit through contacts of two of said switches in succession, and means to control the extent
- 15 of movement of said switches in accordance with the actuated or non-actuated condition of said relays.
9. In a telephone exchange system, a plurality of link circuits arranged in groups, an operator's telephone set, a primary automatic switch to extend connection from said telephone set to a desired group, a secondary

automatic switch individual to each group, a key associated with each of said link circuits, a group of locking relays to control 25 group selection, a secondary group of locking relays to control individual link selection, means to actuate a relay in each of said groups upon momentary depression of one of said keys, means to control the 30 extent of movement of said primary switch in accordance with which one of said group selection controlling relays has been actuated, and means to control the extent of movement of said secondary switches in accordance with which one of said individual link selection controlling relays has been actuated, to extend connection from said telephone set to a desired link circuit.

In witness whereof I hereunto subscribe 40 my name this 27th day of October, A. D. 1917.

ALBEN E. LUNDELL.
